Joe A. Stone, Chicago, Ill., assignor of one-half to
Millard A. Stone, Chicago, Ill.

Application October 2, 1946, Serial No. 133,694

Term of patent 14 years

(Cl. D26—1)

To all whom it may concern:

Be it known that I, Joe A. Stone, a citizen of the United States, residing at Chicago, county of Cook, and State of Illinois, have invented a new, original, and ornamental Design for a Metal Anode, of which the following is a specification, reference being had to the accompanying drawing forming a part thereof, in which:

Figure 1 is a side view in elevation of a metal anode, showing my new design;

Fig. 2, a plan view;

Fig. 3, an end elevational view showing the end at the righthand side of Fig. 2; and

Fig. 4, a perspective view showing the end at the lefthand side of Fig. 2.

I claim:

The ornamental design for a metal anode, as shown.

JOE A. STONE.
